DESIGN FOR A PUMPING UNIT FOR HOSPITAL USE

Edmond O. Pratt, Los Angeles, Calif.

Application October 18, 1947, Serial No. 142,006

Term of patent 3½ years

(Cl. D83—1)

To all whom it may concern:

Be it known that I, Edmond O. Pratt, a citizen of the United States, residing in the city of Los Angeles, county of Los Angeles, and State of California, have invented a new, original, and ornamental Design for a Pumping Unit for Hospital Use, of which the following is a specification, reference being had to the accompanying drawings, forming a part thereof.

Fig. 1 is a perspective view of the pumping unit

for hospital use, showing my new design, taken from the front and one side thereof, and Fig. 2 is a perspective view of the unit taken from the rear and the other side thereof.

I claim:

The ornamental design for a pumping unit for hospital use, as shown.

EDMOND O. PRATT.
